I. KREBS.

Whiffletree.

No. 12,911.

Patented May 22, 1855

Fig. 2.

Fig. 1.

UNITED STATES PATENT OFFICE.

ISAAC KREBS, OF WINCHESTER, VIRGINIA.

WHIFFLETREE.

Specification of Letters Patent No. 12,911, dated May 22, 1855.

To all whom it may concern:

Be it known that I, ISAAC KREBS, of Winchester, in the county of Frederick and State of Virginia, have invented and made certain new and useful Improvements in Swingle or Whiffle Trees for Disengaging Horses from Vehicles; and I do hereby declare that the following is a full, clear, and exact description of the method of construction and mode 10 of operating the same, reference being had to the accompanying drawings, making a part of this specification, in which—

Figure 1, is a diagram of the detachable whiffle tree *a, a, a, a*, showing the horizontal 15 bolts, or trace, or tug holders, *b, b, b, b*, closed, or as presented when the tracing is connected or fastened therewith; *c, c*, the triple pivot, or fulcrum lever, attached to the rods *b, b*, by the staple or fork standard, 20 or holder *d*; *e, e*, the flexible spring. *f, f*, are the end, clevis clips, or tug ends to the tree. *g, g*, are the end ferrules or bands. *h*, is the pull by or attaching clip. *i, i*, are guide staples to the bolts *b, b, b, b*. *j*, the 25 lower part or connection end of clip. *k* the eye or thong ring to the lever *c, c*. *m, m* the thong of slip cord. *n* the handle or holder.

Fig. 2, shows the whiffle tree and the position of the rods or bolts, *b, b*, and the lever 30 *c, c*, when the tracing or tugs are detached.

In order to enable others to construct and use my improved disengaging whiffle tree, shown in the drawings, I will herewith describe the construction thereof which consists first of using a whiffle or single tree, of wood or metal in form similar to those used ordinarily, to the ends of which I attach clevis like staples, or tug holders, *f, f*, and rivet or screw the ends thereof on permanently, and in addition thereto I attach thin metal bands or ferrules, *g, g*. These clevis like clips, or tug holders, may be merely large enough to admit of the trace ends to pass in and out freely. Next a groove or 45 depression is formed longitudinally on the back part of the tree, in the middle, or nearly midway of the ends of the tree, into which is inserted and attached by one end a flexible spring, four or five inches long, as at 50

e, e. Next a forked staple device or equivalent standard device or holder, *d*, is formed and may be attached to the back part of the tree either in the center, midway between each end, of the tree, or two or three inches 55 to the right or left of the center of the tree. Next a lever of about six or eight inches

long, by about half an inch wide, and one fourth of an inch thick, and tapering toward one end, which is turned up in form of a hook or having a ring, to which may be attached a thong slip cord. The broad or butt end of this lever, has three holes punched through it at equal distances about an inch apart, and longitudinally of the length of the lever. The center or middle 60 hole, of the lever, is for the attachment to the staple or standard *d*, by bolt or pin or rivet. Next two rods, or small bars, of rod iron or stout wire, of sufficient length, and of about one fourth of an inch, or more in 65 diameter, one end of each of the said rods being split or formed with a fork, the splits of which are to be punched with pin or rivet holes, and the said rods are attached, each to one of the holes of the lever, *c, c*. These 70 rods must be attached so as to work or play sufficiently on the lever. The said rods are used as the tug or trace bolts, or fastenings, and are kept in their places by small staples or equivalents *i, i*, driven into the 75 back part of the whiffle tree, and answer also as guides or rests for the brace fastening rod; one or more of the staples or guides may be used to each rod.

In the application of my whiffle tree to 80 vehicles, all that is essential is to form a bolt or linch pin hole, through the center of the top of the tree and use a pull by connection clip *h, j*, to attach the tree to the cross bar, or heel rail of the shafts of single horse vehicles; and when double harness are to be used, it is only requisite to apply two of my 85 whiffle tree. The levers *c, c*, working right and left, as may best suit, and then in order to connect and operate the two levers by one 90 common operation, a thong or slip cord, or its equivalent, may connect from one lever to the other and may be arranged to pass up under, and through the foot or bottom part of the dash board, or front of the vehicle for 95 greater convenience, when attached to carriages or light vehicles. For wagons, carts and other heavy vehicles, the pull string or slip thong *m, m*, may be used in any convenient manner.

The operation of my whiffle tree is as follows. When it becomes necessary to disengage fractious or unruly and runaway horses, all that is necessary to be done is to pull the slip thong *m, m, m*, by the holder 100 *n*, the lever *c, c*, being attached to the sliding bolts, or tug or trace rods, *b, b, b, b*, causes

the rods to draw inward toward the center of the tree, and as they draw inward simultaneously, the tugs, or traces become detached, and the fractious animal is most 5 readily disengaged. The rods are kept back in their required position by the action of the spring *e*, *e*, as shown in Fig. 2.

When the traces are to be attached the lever *c*, *c* is thrown back, parallel with, and 10 against the rod, and is kept in its place by the pressure of the spring *e*, *e*, and when the traces or tugs are attached the rods *b*, *b*, *b*, *b*, are distended, as in Fig. 1.

The advantages of my form of construction, 15 and my mode of operating whiffle trees for the disengaging of unruly animals from vehicles, are simplicity of construction, durability, cheapness, and effectual action; together with the least liability to get out of 20 order.

In the description of my improved whiffle tree, I do not wish to be understood as setting up any claim to the construction of the usual form of a whiffle tree, nor of any of 25 the devices used separated and apart from each other, being well aware that many devices, forming a whiffle tree for the disengaging of animals from vehicles, have been

made and used, in many forms, with sliding bolts, and spiral or helical springs, in combination with separate and distinct levers, operated by connecting links or cords, but none of these devices, or their combinations, as set forth do I claim; but to distinguish my said improvements from such as are in 35 general use, I herewith specifically set forth the particular new features of my improvements, and desire to have secured by Letters Patent of the United States,

The construction of a whiffle tree with 40 continuous sliding bolts, or trace fastening rods *b*, *b*, *b*, *b*, communicating directly with, and attached to one single and the same lever, together with the staple *d*, one single flexible spring *e*, *e*, clevis clips *f*, *f*, in combination, and through all of which, are actuated, and retained in position, simultaneously, at one and the same time, the continuous sliding bolts *b*, *b*, substantially in the manner shown in Figs. 1 and 2, and as described, for the purpose set forth.

ISAAC KREBS. [L.S.]

Witnesses:

JOHN L. SMITH,
P. B. BELL.
